ELECTRIC CONTROLLER.

Application filed March 3, 1922. Serial No. 540,817.

This invention relates to improvements in electric controllers designed particularly for use in connection with lifting magnets, though capable of use for many other purposes.

Electric controllers, particularly those adapted for use with lifting magnets, must be positive in performance and the possibility of accidental opening of their contacts must be obviated or, at least, minimized. Furthermore, such controllers must be constructed to stand up under very hard service conditions in operating lifting magnets and also give maximum protection to the windings of the magnet. The destructive arcing of contacts must be prevented and discharge protection must be afforded the lifting magnet. Such protection must be attained without the dangerous introduction of the usual fuses or circuit-breakers into the circuit of the lifting magnet. As is well known, fuses often blow without apparent cause and circuit-breakers often function from excessive vibration. In either case, no discharge protection is afforded the magnet. The danger resides not only in damage or injury usually resultant from such sudden unexpected release of the lifted load but also in damage to the magnet windings and to the load or either.

In this improved controller two magnetic blowout coils have been provided, one for each of the two lines. Further, each of the two lines is provided with two contact openings and preferably all such openings are concentrated as much as feasible and set in a straight line. These coils are so located that the controller case, which is preferably of iron, forms one of the magnetic circuits while the other path of the magnet lines of force passes through the line of contact fingers. These blowout coils are also designed to function as choke coils and are constructed to carry a limited amount of current. These blowout coils are easily interchangeable and replaceable giving an added advantage to the controller of adaptability to variant duties and of variant capacities. The above-mentioned obviation or minimizing of accidental contact opening is effected by positive locking of contacts so that opening through vibration or accidental striking against the operating lever will not pull the

contacts out of their operative lifting position. This positive locking is effected by the provision of a locking pin, at the operating end of the controller, to lock the contacts in lifting position. This pin also gives a quick make-and-break or snap action of contacts.

The object therefore of the invention is to provide an improved electric controller.

More specific objects of the invention are to provide a controller by means of which electric circuits may be made and broken without forming any arc; to provide a controller with two powerful magnetic blowers; to provide an instantaneous make and break of the controller contacts; to provide reliable and effective discharge clips and resistance; and to provide suitable resistance for the reverse current in dropping the load from the magnet.

Other objects of the invention will appear from the following detailed description, taken in connection with the accompanying drawings, in which—

Figure 1 is an elevation of my improved controller, with the outer casing removed;

Figure 2 is a vertical section on line 2—2 of Figure 1;

Figure 3 is a plan view;

Figure 4 is a horizontal section on line 4—4 of Figure 2;

Figure 5 is a vertical section on line 5—5 of Figure 4;

Figure 6 is a similar view on line 6—6 of Figure 4; and

Figure 7 is a detail section on line 7—7 of Figure 2.

The casing of the device is preferably provided by a one-piece or integral casting forming the back wall 2 and the top and bottom, or upper and lower end walls 3 and 4. This casing is also preferably provided with lugs 5 by means of which the controller may be secured to a vertical wall or support in the position indicated in Figure 1 of the drawings. The edges of the rear end walls are preferably recessed so as to receive, and make a close joint with, an enclosing casing or outer cover 6. This cover is shown as formed of sheet metal with an insulating lining 7 and having its vertical edges secured to the edges of the rear wall 2 by suitable screws 8. While the casing may be of any desired form it is preferred to

make its outwardly projecting part of curved form (Figures 3 and 4).

A bar 9 having journals 10 and 11 is arranged in a vertical position in the casing. The journals 10 and 11 are preferably mounted to rotate in bearings in the upper and lower walls 3 and 4. The bar 9, thus supported, is capable of being oscillated on its vertical axis, for the purpose hereinafter stated. A block 12 is arranged upon the upper journal 11 of the bar 9 and is secured rigidly to said journal preferably by a suitable set screw 13. This block is preferably circular in cross-section and is provided upon its edge with three depressions 15 (Figures 2 and 7) adapted to be engaged by the rounded end of a spring-bolt 16 disposed in a suitable socket in the wall of the casing and pressed outwardly toward said block 20 by a compression spring 17.

A crank arm 18 is mounted to turn freely upon the journal 11 and is provided with a handle 19. This crank is held upon said journal by means of a set screw 20 engaging an annular groove 21 in said journal. The crank arm 18 is provided with a pair of lugs 22 extending downwardly beyond the plane of an integrally projecting arm 14 on the block 12. A tension spring 23 is connected 30 to the end of the arm 14 and to a lug 24 provided on the end of the crank arm 18. Bosses 18^a are provided on the top wall 3 to limit the horizontal movement or throw of the crank arm 18.

The bar 9 is preferably provided upon one side thereof with parallel flanges 25, (see Figure 4) and the space between said flanges forms a groove in which is secured a longitudinally extending block or bar 26 of insulating material.

Contacts 27 and 28 (see Figure 5) are preferably secured upon the outer edge of the bar 26. Each of these contacts is preferably of U-shape and is secured to the bar 26 by suitable screws 29. Each contact is also preferably provided at the free end of each of its arms with a broad contact block presenting a contact surface 30. These contact surfaces are adapted to engage suitably disposed contact blocks. Secured upon the rear wall of the casing are the longitudinally extending bars 31 and 31^a of insulating material (see Figures 4 and 5). The bar 31 has secured to it a series of metal conducting plates 32^a, 32^b, 32^c, and 32^d, (see Figures 1 and 2) while the bar 31^a has a corresponding series of plates 32^e, 32^f, 32^g and 32^h. Secured to said plates are the spring contact fingers 33 preferably arranged in pairs, each carrying contact blocks 34. These blocks are disposed for engagement by the contact blocks 30 (Figure 4) as hereinafter set forth. A wall or separator 30^a of insulating material is provided at each end and 65 also between each pair of contact fingers to

prevent arcing between said fingers. These walls are held in place by recesses or slots provided in bars 31, 31^a, Figure 4 and also bar 35, hereinafter described.

The vertically extending bar 35 of insulating material, preferably secured to the end walls 3 and 4 of the casing by suitable screws 36 (Figures 2 and 4), is arranged parallel with the oscillating bar 9, and substantially at the outer wall of the casing. This bar has supported thereon the two pairs of oppositely extending curved clips 37 and 37^a, held in place by bolts 38 and 38^a, Figure 1. These bolts also form connecting means for electric conductors as hereinafter described.

Extending through one wall of the casing preferably the lower wall 4, are several pairs of conductors, consisting preferably of usual insulated wires, each provided with an ordinary connecting clip 39. These wires preferably extend through insulating bushings 40 arranged in openings in the wall of the casing. As indicated in Figure 6 the wires 41 and 42, connect with the main line or source of electric power. The conductors 43 and 44 connect with a lifting magnet, or any other device that it is desired to operate by an electric current passing through this controller. Conductors 45 and 46 connect with a discharge resistance and conductors 47 and 48 with an unloading resistance. The conductor 41, extending from the main line, connects with the plate 32^c through a suitable magnetic blow-out coil 49, and the other main line conductor 42 connects with the plate 32^d through a similar blow-out coil 50.

The conductor 43 is connected to the plate 32^e and the conductor 44 is connected to the plate 32^g. The conductor 47 is connected to the plate 32^e and the conductor 48 to the plate 32^h. The conductor 45 is connected to the bolt 38 that is connected with the clips 37, while a conductor 51 extends from the plate 32^c and is connected with a bolt 38^a having electrical connection with the clips 37^a. Plates 32^a and 32^h are permanently connected by conductor 52. Plates 32^b and 32^d are permanently connected by conductor 53. Plates 32^c and 32^g are permanently connected by conductor 54.

Operation.—The top wall of the casing 3 is preferably provided upon its outer surface with the words "Lift", "Off" and "Drop", indicating the three positions into which the oscillatory bar 9 carrying the contacts 26 and 27 may be turned by the crank 18 and handle 19.

Assuming that the bar 9 stands in the position shown by full lines in Figure 4 the contact blocks or surfaces 30 on the swinging contacts 27 and 28 will be in electrical engagement with the blocks 34 carried by the contact springs 33 on the "lift" side of

the controller. A circuit will then be closed from the generator through the conductor 42, the blow-out coil 50, plate 32^a, its spring 33 and block 34, the swinging contact 28, block 34, spring 33, plate 32^a, conductors 54 and 44, to the magnet. The return from the magnet is through conductors 43, 53, plate 32^b, spring 33, block 34, the swinging contact 27, block 34, spring 33, plate 32^a, conductor 41 and blow-out coil 49, to the generator. By this means the lifting magnet will be energized and may be employed for lifting and transporting any desired metallic articles.

Assuming now that it is desired to deenergize the magnet in order to cause it to release the article or articles held by it, the handle 19 and crank arm 18 will therefore be swung from the position indicated by dotted lines opposite the word "Lift" in Figure 3, to the position shown by dotted lines opposite the word "Drop" in the same figure. As the block 12 is held in a stationary position by the spring bolt 16 (Figure 7), the bar 9 will also remain in a stationary position until the crank arm 18 has been swung a sufficient distance to cause one of the lugs 22 on the crank arm to engage the lug 14 on the block 12. This movement of the crank arm, while the block remains stationary, will put the spring 23 under tension. As further movement of the crank arm will, by the engagement of the lug 22 with the lug 14, cause the block 12 to be turned with the crank arm, the rounded end of the spring bolt 16 slipping out of the recess 15 in the edge of the block 12. The tension of the spring 23 will act to give a quick quarter turn to the bar 9, turning it to the position indicated in dotted lines in Figure 3 opposite the word "Off."

As soon as the swinging contacts 27 and 28 carried by the bar 9 are moved away from the contact blocks 34 carried by the springs 33 the circuit already described through the magnet will be broken, and an arc will be formed between the contact blocks 30 and 34. Under the action of the coils 49 and 50, however, these arcs will be blown out in a manner well understood in the art so that there will be no injury to the contact blocks 30 and 34.

The spring 23 being under tension when the block 12 is released from the spring bolt 16, will quickly turn the bar 9 so as to bring said bar into the intermediate position shown by the dotted lines in Figure 4, the second recess 15 on the edge of the block 12 being engaged by the spring bolt 16, which stops the movement of the bar 9, and holds said bar in a stationary position. As the operator continues the movement of the handle 19 and the crank arm 18, while the block 12 remains stationary, the spring 23 is again put under tension and, when the lug 22 en-

gages the lug 14 on the block 12, the two parts will move together and the block 12 will be released from the spring bolt 16. The tension of the spring 23 will then quickly throw the lug 14 forward, turning the block 12 and bringing the parts into the position shown by dotted lines at the left in Figure 4. The blocks 30 on the contacts 27 and 28 are thus brought into electrical contact with the blocks 34 on the spring contact fingers 33 carried by the plates 32^a, 32^b, and 32^c.

As the contact block 30 carried by the swinging contact 28 are moved away from the blocks 34 carried by the springs 33 connected with the plates 32^a and 32^b, they come into contact with the clips 37 and 37^a. Connection is then made through said clips and the movable contact 28 bringing the discharge resistance which is to be connected with the conductors 45 and 46 into direct circuit with the magnets, whereby the discharge current of the magnet is absorbed in the discharge resistance. The circuit is as follows: One side of the magnet, conductor 44, conductor 51, spring clips 37^a, swinging contact 28, clips 37, conductor 45 through the discharge resistance, conductors 46 and 43, to the other side of the magnet.

When the movable contacts 27 and 28 are brought into connection with the contact on the springs carried by the plates 32^a, 32^b, 32^c and 32^d, the unloading resistance connected with the conductors 47 and 48, will be brought into circuit with the magnet and the polarity of the current through the magnet will be reversed, thereby bringing the magnet to zero and causing the load to be immediately dropped by the magnet.

This circuit is as follows: One side of the main line, conductor 42, blow-out coil 50, conductor 48, through unloading resistance connected with the conductors 47 and 48, conductor 47, plate 32^a through its spring and block, through block 30, swinging contact 29, plate 32^b with its spring and block, conductor 43 through the magnet, conductor 44, plate 32^c with its contact block, swinging contact 28, plate 32^d through its spring and block, conductors 52 and 41, blow-out magnet 49, and conductor 41, to the other side of the main line. It will be noticed that the current in this case traverses the magnet in the opposite direction from which it does when the arm 18 is thrown to the lift position.

As soon as the magnet has dropped the load the operator will turn the handle and crank arm 18 into the position indicated by dotted lines after the word "Off" in Figure 3, and the bar 9 will then stand in the neutral position indicated by the dotted lines at the center in Figure 3.

I claim as my invention:

1. In an electric controller the combina-

tion with a casing, insulating blocks supported at intervals around the interior walls of the casing, an insulating bar journaled in the casing to oscillate therein intermediate the blocks, contact members carried by the insulating blocks and the insulating bar respectively, insulating strips substantially horse-shoe-shaped and embracing the oscillatable journaled bar, said strips being located between the contacts and supported at each end and middle portion by said insulating blocks.

2. In an electric controller, the combination with a casing, insulating blocks supported at intervals around the interior walls of the casing, an insulating bar journaled in the casing to oscillate therein intermediate the blocks, contact members carried by the insulating blocks and the insulating bar respectively, insulating strips substantially horse-shoe-shaped to leave space for the oscillation of the journal bar, said strips being located between the contacts and supported at each end and middle portion by said insulating blocks, said insulating strips being spaced from the casing, and blow-out coils on the end of the casing and connections therefrom to said contacts extending through the space between said strips and the casing.

3. In an electric controller the combination with a casing having a back, a top, and a bottom, and having the front thereof substantially semi-cylindrical, of an oscillatable bar journaled in the top and bottom of said casing, U-shaped contact members carried by said oscillatable bar and adapted to engage with contacts disposed within the sweep of said bar as it is swung from one extreme position to the other, a plurality of insulating bars carrying contacts thereon mounted in said casing and having the contacts thereof so disposed as to be within the sweep of the contacts of said oscillatable bar, substantially semi-circular insulating separators mounted in slots in said last named insulating bars and disposed between contacts to prevent arcing therebetween.

4. In an electric controller the combination with a casing having a back, a top, and a bottom, and having the front thereof substantially semi-cylindrical, of an oscillatable bar journaled in the top and bottom of said casing, U-shaped contact members carried by said oscillatable bar and adapted to engage

with contacts disposed within the sweep of said bar as it is swung from one extreme position to the other, a plurality of insulating bars carrying contacts thereon mounted in said casing and having the contacts thereof disposed to be within the sweep of the contacts of said oscillatable bar, substantially semi-circular insulating separators mounted in slots in said last named insulating bars and disposed between contacts to prevent arcing therebetween, and a pair of blow-out coils disposed in line with part of said contacts, the magnetic circuit of said coils including said casing.

5. In an electric controller, a semi-cylindrical casing, a bar journaled in the ends of the casing, an insulating bar attached to a side of the journal bar and having pairs of contacts attached thereto, insulating blocks attached to the flat side of the casing and a third insulating block to the semi-cylindrical portion of the casing intermediate the first-mentioned blocks, said blocks having contacts thereon to co-act with the contacts on the insulating bar, horseshoe-shaped insulating strips having their diametrically opposite ends attached to the two blocks at the flat side of the casing and also supported by a third insulating block intermediate the first two blocks, said strips extending between contacts supported on the insulating blocks, and a journal on the journal bar extending through the casing at one end, and means on the journal exterior of the casing for quick making and breaking of the circuits through the contacts.

6. A controller comprising a casing, an oscillating contact maker, insulating blocks on opposite sides of the casing, and a third insulating block, midway of the sweep of the contact maker as it oscillates in the casing, contact plates carried by each of the first mentioned insulating blocks, each plate carrying a plurality of contacts, a plurality of contacts carried by the intermediate insulating block and extending in opposite directions from said third insulating block, the contacts being so arranged that as the oscillatable contact maker is oscillated the contacts thereon will engage successively the contacts on said blocks.

In witness whereof, I have hereunto set my hand this 27th day of January, 1922.

JOHN E. SEDERHOLM.
